UNITED STATES PATENT OFFICE

160,174

CHRISTMAS ORNAMENT OR SIMILAR ARTICLE

Arnold Janowitz, New York, N. Y.

Application June 15, 1949, Serial No. 3,297

Term of patent 3½ years

(Cl. D29—1)

To all whom it may concern:

Be it known that I, Arnold Janowitz, citizen of the United States of America, residing at New York, in the county of New York and State of New York, have invented a new, original, and ornamental Design for a Christmas Ornament or Similar Article, of which the following is a specification, reference being had to the accompanying drawing, forming part thereof.

Fig. 1 is a perspective view of a Christmas ornament or a similar article, showing my new design, and

Fig. 2 is a front view thereof in a folded position.

I claim:

The ornamental design for a Christmas ornament or similar article, as shown.

ARNOLD JANOWITZ.
